EDWARD F. KELLEY, OF BRIDGEPORT, CONNECTICUT, ASSIGNOR TO THE RAYBESTOS COMPANY, OF BRIDGEPORT, CONNECTICUT, A CORPORATION OF CONNECTICUT.

DETACHABLE EAR FOR TRANSMISSION BANDS.

Application filed August 28, 1924. Serial No. 734,657.

To all whom it may concern:

Be it known that I, EDWARD F. KELLEY, a citizen of the United States, residing at Bridgeport, county of Fairfield, State of Connecticut, have invented a new and useful 5 Detachable Ear for Transmission Bands, of which the following is a specification.

This invention relates to transmission and 10 brake bands for automobiles, and especially to a removable ear for the bands of the Ford type of transmission.

It is well known that the Ford type of 15 transmission comprises three rotating drums, one for the low speed, the reverse and brake respectively, located closely adjacent each other and enclosed in a casing including a cover comprising substantially the entire upper half of the casing, and which cover has a small opening in the top thereof over these 20 drums which is closed by a hand plate. Each drum is substantially encircled by a flexible steel band lined with asbestos or other suitable material, and is provided at its ends with forked ears engaged by the 25 operating rod connected to the familiar operating pedal for clamping the band about its drum. It is obvious that after the mechanism has been in use for some time the asbestos or other lining for the bands wear out 30 and must be renewed. Owing to the peculiar construction of the transmission and transmission cover, in order to replace any of the linings it is necessary to remove and replace the entire transmission cover, an operation 35 which requires considerable skill and time.

In order to overcome these objections I 40 have constructed a band for this type of transmission having a detachable ear which may be removed through the hand opening and allow removal of the band without the necessity of removing the cover of the transmission casing. I have also devised an improved means for securing the ear to the band which may be easily released to allow 45 removal of the ear, but which will securely lock the ear to the band and prevent accidental release thereof in operation. This securing means is also so arranged that the ear may be removed from and applied to the band by a simple movement radially of the band without the necessity of any sliding movement upon the band, as the space available in the casing is very limited.

With the foregoing and other objects in 55 view I have devised the construction illus-

trated in the accompanying drawing forming a part of this specification, similar reference characters being used throughout the various figures to indicate corresponding elements. In this drawing

Fig. 1 is a side view of the upper portion of a band, showing my improved securing means for a detachable ear, one ear being shown in elevation and the other in longitudinal section.

Fig. 2 is a plan view of the ear and the attaching means therefor.

Fig. 3 is a transverse section substantially on line 3—3 of Fig. 1 showing the catch in securing position and on an enlarged scale, 70 and

Fig. 4 is a similar view showing the catch released.

The band comprises the usual strip of 75 flexible steel 10 to which the asbestos or other suitable lining 11 to engage the rotating drum is secured. The forked ears are indicated at 12 and 13, the recess 14 being arranged to receive the operating rod. The operating mechanism is not shown as its 80 construction is well known and forms no part of my invention. The ear has a curved body portion 15 to substantially correspond with the curvature of the band.

The means for detachably securing the ear 85 to the band includes a pair of spaced outwardly extending lugs 16. These lugs may be formed in various ways but are preferably formed by cutting the band with a substantially U-shaped cut as indicated by dotted 90 lines 17 Fig. 2, and bending outwardly the metal enclosed by this cut at the uncut side, so that the lugs are integral with the band. The curved body of the ear is provided with a pair of spaced elongated openings 18 to 95 receive these lugs, and a catch 19 is pivoted to the ear at 20 between these openings. The catch is provided at its opposite ends with extensions 21 extending laterally in opposite directions, and which are adapted to 100 project into transverse openings 22 in the lugs 16 to secure the ear to the band. In order to prevent accidental release of this catch, the ends 21 are bent outwardly slightly as shown in Figs. 3 and 4, and the catch 105 itself is made of resilient material with its free ends spaced outwardly a short distance from the body of the ear. After the ear has been placed on the band with the lugs 16 extending through the openings 18 the free 110

ends of the catch are pushed toward the body of the ear against the resiliency of the catch and then the catch is rotated to insert these free ends in the transverse openings 22. The free ends then tend to move outwardly under the spring action of the catch and the outwardly bent portions will engage the side of the openings and prevent accidental release of the catch in operation. 10 It will be apparent, however, that the catch may be swung to the released position as shown in dotted lines Fig. 2, and that then the ear may be removed from the band by merely lifting it radially away from the band. 15

It will be apparent that this construction is very simple and it may be manufactured at relatively low cost, but that the ear is rigidly attached to the band by a structure 20 which will lock it thereto so that there is practically no danger of its working loose in operation. It may, however, be very easily and quickly removed and applied in the small space available in the transmission 25 casing. After the ear has been removed the band may be removed from the casing through the hand opening in its top.

Having thus set forth the nature of my invention what I claim is:

30 1. In a transmission or brake band, a strip of flexible material, provided with a lug extending outwardly therefrom having a transverse opening therein, an ear having an opening to receive said lug, and a securing 35 means movably mounted on the ear and provided with a portion to extend into said transverse opening to secure the ear to the band.

40 2. A transmission or brake band comprising a curved strip of metal having an outwardly extending lug struck therefrom provided with a transverse opening, an ear having an opening to receive said lug, and a catch pivoted to the ear having a portion to extend into said transverse opening to secure the ear to the band. 45

50 3. A transmission or brake band comprising a curved strip of metal provided with a lug extending outwardly therefrom having a transverse opening, and a catch movably mounted on the ear and having a portion to extend into the transverse opening to secure the ear to the band, said catch being resilient

and having a laterally extending portion engaging a side of the opening to prevent accidental release of the catch. 55

4. A transmission or brake band comprising a curved strip of metal provided with a lug extending outwardly therefrom having a transverse opening, and a catch pivoted to 60 the ear and having a laterally extending portion to extend into said transverse opening to secure the ear to the band, said catch being resilient with its free end tending to move outwardly and said lateral portion being provided with an outwardly extending portion to engage the lug under the spring action of the catch. 65

5. A transmission or brake band comprising a curved strip of metal having a pair of 70 spaced outwardly extending lugs having transverse openings, an ear having openings to receive said lugs, and a catch pivoted to the ear between said openings and provided with lateral extensions at the opposite ends 75 thereof to extend into the openings in the lugs.

6. A transmission or brake band comprising a curved strip of metal having a pair of spaced outwardly extending lugs having 80 transverse openings, an ear having openings to receive said lugs, and a catch pivoted to the ear between said openings and provided with lateral extensions at the opposite ends 85 thereof to extend into the openings in the lugs, said lateral extensions being bent outwardly at their free ends and the catch being resilient and tending to move its free ends outwardly. 90

7. A transmission or brake band comprising a curved strip of metal having a pair of spaced lugs cut therefrom and bent outwardly about one edge, said lugs being provided with transverse openings, an ear provided with spaced openings to receive said lugs, a resilient catch pivoted at substantially its center to the ear between said openings, the opposite ends of the catch extending laterally and outwardly, said ends being adapted to enter the openings in the lugs to secure the ear to the band, and said outwardly extending ends coacting with the lugs under the spring action of the catch to prevent accidental release of said catch. 95 100

In testimony whereof I affix my signature.
EDWARD F. KELLEY.
